UNITED STATES PATENT OFFICE

154,538

DESIGN FOR A SEMIRIMLESS SPECTACLE
FRONTJames J. Gullen, Rochester, N. Y., assignor to
Rochester Optical Manufacturing Co., Inc.,
Rochester, N. Y., a corporation of New York

Application March 5, 1948, Serial No. 144,927

Term of patent 14 years

(Cl. D57—1)

To all whom it may concern:

Be it known that I, James J. Gullen, a citizen of the United States, residing at Rochester, in the county of Monroe and State of New York, have invented a new, original, and ornamental Design for a Semi-Rimless Spectacle Front, of which the following is a specification, reference being had to the accompanying drawing, forming part thereof.

Figs. 1 and 2 are front and rear elevations, respectively, of a semi-rimless spectacle front, showing my new design, the lenses of the spectacle being shown in dotted lines; and

Fig. 3 is a plan view of the spectacle front.

The essential features of my design for a semi-rimless spectacle front are shown in full lines, the dominant features being the surface ornamentation, particularly the line extending

longitudinally on the top of the spectacle front, as seen most clearly in Fig. 3, all as illustrated on the drawing.

I claim:

The ornamental design for a semi-rimless spectacle front, as shown and described.

JAMES J. GULLEN.
